UNITED STATES PATENT OFFICE.

HARRY J. VALENTINE, OF CLEVELAND, OHIO, ASSIGNOR TO THE COLUMBIAN HARDWARE COMPANY, OF CLEVELAND, OHIO, A CORPORATION OF OHIO.

SPRING-HINGE.

SPECIFICATION forming part of Letters Patent No. 734,447, dated July 21, 1903.

Application filed November 18, 1902. Serial No. 181,823. (No model.)

To all whom it may concern:

Be it known that I, HARRY J. VALENTINE, a citizen of the United States of America, and a resident of Cleveland, Cuyahoga county, in 5 the State of Ohio, have invented certain new and useful Improvements in Spring-Hinges, of which the following is a specification.

This invention relates to spring-hinges of the class, whether single or double, which are 10 applied to the door and door-frame unset, but which are so constructed that after screwing them in position their springs may be tightened up and placed under tension.

The objects of the present invention are, 15 first, to so construct the tubular pintle on which the hinge-knuckles turn that the operating-spring may be readily and conveniently set from an intermediate point on the hinge; second, to provide ample and smooth 20 antifriction-bearings for the knuckles, and, third, to provide the hinge with a checking device against the slamming of the door to which the hinge is applied.

Further objects are to provide a spring- 25 hinge which will be efficient in action and which overcomes some of the defects of those now on the market.

My invention consists of certain features of construction and combinations of parts, to 30 be hereinafter described in detail and then pointed out in the claims.

In the accompanying drawings, Figure 1 is a side elevation of a hinge made in accordance with the present invention, the leaves 35 being shown closed. Fig. 2 is a plan view with the leaves closed and the upper tip or knob and its rivet removed. Fig. 3 is a detail of the upper part of the hinge, partly broken away to disclose the parts inside the 40 tip and tubular pintle. Fig. 4 is a transverse section through the base of the tip and interior parts with the leaves in plan and opened out fully. Fig. 5 is a longitudinal section of the central portions of the hinge, the leaves 45 being shown opened out in elevation. Fig. 6 is a detail perspective view of the cup or disk to which the upper end of the operating-spring is applied. Fig. 7 is a detail perspective view of the cup or disk to which the upper 50 end of the check-spring is applied. Fig.

8 is a detail perspective view of the upper section of the tubular pintle, and Fig. 9 is a detail perspective view of one of the washers between the knuckles.

While in the drawings the invention is 55 shown as applied to a single hinge, it is to be understood that the invention is equally applicable to a double hinge.

The hinge-leaves A B are provided with knuckles *a b*, respectively, through which 60 the tubular pintle composed of sections C C' passes. Preferably the lower section C' is provided with a capstan-ring D, slipped over it and secured on it by a set-screw *d* and located between the two middle knuckles of the 65 hinge shown, which knuckles bear at their adjacent edges upon the said ring. This ring has a suitable number of holes *d'* for receiving a locking-pin *d''*, which is inserted in position in one of them and is engaged by the 70 leaf B in opening the hinge for straining the main or operating spring to be described. The upper section C of the tubular pintle is secured to upper knuckle *a* of leaf A by a set screw or screws *c*, and the lower section C' 75 is free to be adjusted in the lower knuckles. Set-screw *c* screws also into the flange of a cup or flanged disk E, which is located in the upper end of tubular section C. An axial opening *e*, for the purpose to be stated later, 80 is formed in the cup E, and a hole *e'* is located in the disk at one side thereof to receive the upwardly-bent upper end *f* of the helical main or operating spring F, the diameter of which is nearly that of the inside of the tubular pintle. A downturned lower end *f'* on the spring F is engaged in a side hole *g*, located in an inverted cup or flanged disk G, secured in the lower end of the tubular section C' by set screw or screws *c'*. The spring 85 F simply engages in the holes *e' g* at both ends and requires no other fastening. To tighten the spring, a short lever or nail is inserted into one of the holes in the capstan-ring D and the locking-pin *d''* set behind leaf 90 B, the lever being reinserted, the ring being turned, and the locking-pin reset until a sufficient tension is placed on the spring. The method of doing this is well known.

The lower knob or tip H is secured to the 100

pintle-section C' by the described set-screw c', and the upper knob H' is placed onto the upper end of the upper pintle-section C, it being secured in position in the manner to be described later.

Between the knuckles a b of the hinge-leaves are suitable bearings formed by preferably dished collars or washers I I', which are only slightly larger in internal diameter than the tubular pintle and which are arranged in pairs, placed with their concaved faces together, preferably to form raceways for antifriction-balls j. These collars I I' are provided with outturned key-lugs or projections i, which interlock with corresponding recesses i' in the knuckles, so that one of the collars of one pair between adjacent knuckles is locked or anchored to one knuckle and the other collar is fixed to the other knuckle. The outer contact edges I² of the collars preferably bear upon each other and take up more or less wear. In this event they are made of case-hardened steel to serve as wear-collars, the use of the antifriction-balls then being a matter of choice only. The balls bear on the outer surface of the tubular pintle, so that rolling antifriction-surfaces are not only provided between the knuckles, but also between the knuckles and pintle. The invention further resides in means for checking or retarding the action of the operating-spring just before the door closes, thereby preventing slamming of the door. To this end a helical check-spring K is preferably located in the pintle within and inclosed by the operating-spring F, and as it is somewhat less in diameter and the springs are suitably fixed apart the springs do not interfere by rubbing on each other. The lower end of the check-spring K is bent downwardly at k and is engaged in a hole g' in the lower cup or disk G, while the upper coils of the check-spring pass through the enlarged central opening e in cup or disk E. The upwardly-bent upper end k' of the check-spring is engaged in a hole l in an inverted cup or flanged disk L, which is located in the upper end of the pintle-section C and may turn therein. The rim of the cup or flange of disk L is presented downwardly to abut against and turn on the upwardly-presented rim of the cup or flange of the disk E. A series of holes l' is formed in the flange of cup or disk L, and opposite these holes the pintle-section C has a short transverse slot s, which is also located opposite a series of holes m' in the rim of the upper knob H', the said holes l' registering with the holes m', so that a check or tension pin m² may be inserted in the same. This pin m² puts tension on the check-spring reverse to the tension of the operating-spring, to which end it is adapted to be impinged on by the inner side of the leaf B. The tension on the check-spring is obtained upon tightening the same up by inserting a lever or nail in the holes l' m' and turning the knob H' and cup or disk L until a light tension is imparted to the said spring,

when the check-pin m² is inserted in other of said holes and abuts against that end of the slot m adjacent the leaf B when the leaves A B are opened. The initial tension is such that when the leaves are fully opened the pin m² will be brought, preferably, to position shown in Fig. 4, and when the leaf B closes toward and abuts on said pin the latter acts as a check to the quick action of the operating-spring and prevents slamming of the door, acting contrariwise to the operating-spring.

For holding the knob H' and the cup or disk L in place against accidental separation from the hinge the same are preferably connected by a pin or rivet r, which passes through a transverse slot s' at that side of pintle-section C which is opposite the slot s. The pin or rivet r preferably forms a stop to limit the tension placed on the check-spring.

Having thus described my invention, what I claim as new therein, and desire to secure by Letters Patent, is—

1. In a spring-hinge, the combination of the leaves and knuckles, a tubular pintle inserted through the knuckles, and composed of sections, one of which is attached to one leaf and the other of which is rotatable relatively thereto, a capstan-ring secured on the rotary section and located approximately midway of the hinge, the division between the two sections being located to one side of the said ring, and means for setting the rotary section in adjusted position against one of the leaves, and an operating-spring in and attached to said rotary section to close the leaves, substantially as described.

2. In a spring-hinge, the combination of the leaves and knuckles, a tubular pintle inserted through the knuckles, and an operating-spring and paired collars arranged between adjacent knuckles of the respective leaves for taking up wear by the contact of their faces with each other, one collar of each pair being secured to one adjacent knuckle and the other of the pair being secured to the other adjacent knuckle, substantially as set forth.

3. In a spring-hinge, the combination of the leaves and recessed knuckles, a tubular pintle inserted through the knuckles, an operating-spring, and collars between the knuckles, one provided with a lug inserted in the recess of one adjacent knuckle and the other with a lug inserted in the recess of the other adjacent knuckle, substantially as set forth.

4. In a spring-hinge, the combination of the leaves, an operating or main spring, and a check-spring opposing the action of the operating-spring, substantially as set forth.

5. In a spring-hinge, the combination of the leaves, an operating-spring, and a check-spring of less diameter than and located within the operating-spring, said check-spring serving to check the closing action of the operating-spring when the leaves are about to close, substantially as set forth.

6. In a spring-hinge, the combination of the leaves, the operating-spring, a check-spring

- inclosed within the operating-spring, one end of each spring being fast at one end of the hinge and the other end of each spring being adapted for being tightened, means for tightening up the operating-spring, and means for tightening up the check-spring, said check-spring acting against the operating-spring when the leaves are closing, substantially as set forth. 5
- 10 7. In a spring-hinge, the combination of the leaves and knuckles, a tubular pintle on which the knuckles turn, disks or cups secured inside the pintle at each end, said pintle being sectioned between the disks, and an operating-spring attached at one end to one disk and at the other end to the other disk, said disks being separate and independent of each other, substantially as set forth. 15
- 15 8. In a spring-hinge, the combination of the leaves and knuckles, a tubular pintle on which the knuckles turn, disks secured inside the pintle at each end, said pintle being sectioned between the disks, and an operating-spring attached at one end to one disk and at the other end to the other disk, a check-spring secured to the fixing-disk of the operating- 20
- 25
- spring at one end, the other end of the check-spring passing through an opening in the other disk, and means for tightening up or adjusting the tension of the check-spring, substantially as set forth. 30
9. In a spring-hinge, the combination of the leaves, the operating-spring, and a check-pin arranged between the leaves so as to be out of contact with the leaves when the hinge is opened and to contact with the closing leaf when the same is closing, to check the action of the operating-spring, substantially as set forth. 35
10. In a spring-hinge, the combination of the leaves, the operating-spring, a check-spring, a pin for acting on the spring and against which one of the leaves abuts, and means for limiting the movement of the pin to a portion of the extent of movement of the abutting leaf. 40

Signed at New York, N. Y., this 1st day of November, 1902.
